UNITED STATES PATENT OFFICE.

FREDERICK H. JOHNSON, OF NORTHBORO, MASSACHUSETTS.

PUNCH.

Application filed January 11, 1924. Serial No. 635,524.

To all whom it may concern:

Be it known that I, FREDERICK H. JOHNSON, a citizen of the United States, residing at Northboro, in the county of Worcester 5 and State of Massachusetts, have invented certain new and useful Improvements in Punches, of which the following is a specification.

My invention relates to devices for severing tickets from a strip and is known as a 10 box punch.

The essential objects of my invention are to effectively sever and house tickets after severance; to protect the lateral margins of 15 the ticket strip from the action of the punch; to prevent unauthorized, but facilitate lawful, access to the housed stamps; to afford facile attachment and detachment of the housing to and from its mounting; to 20 conveniently position my device; and to attain these ends in a simple, strong, inexpensive, and easily operable structure.

To the above ends essentially my invention consists in such parts and in such combinations of parts as fall within the scope 25 of the appended claims.

In the accompanying drawings which form a part of this specification,

Figures 1 and 2, are a side elevation and 30 a plan view respectively of my novel device,

Figures 3 and 4, sections of the same on lines 3—3 and 4—4 respectively of Figure 1,

Figure 5, a section on line 5—5 of Figure 2, and 35

Figure 6, a perspective view of the bracket.

Like reference characters indicate like parts throughout the views.

In the form of my invention herein shown 40 a cylindrical body or casing 8 comprises a side wall 9, provided with an internal annular shoulder 10 in which is seated a top plate 11 fastened to the wall in this instance by one or more angle plates 12 with attaching screws 13. The bottom of the body consists of a detachable plate 15 overlapping the edge of the wall and provided with a vertical annular flanged portion 17 adjacent its periphery adapted to slidably engage the wall, and provided with a central circular elevated portion 18, centrally of which is a hollow post or tube 19. The bore 20 of the post is continuous through the center of the

plate 15 except that there is an internal annular shoulder 21 forming a retracted passage 55 22 and cavity 23. The upper portion of the post has an internal thread 24 to engage a thread 25 on a detachable milled plug 27 provided with a central hole 28 in which slides a pin 29 having an enlarged head 30 60 upon its lower portion slidably engaging the wall of the bore 20, and provided with a conical terminal portion 31. A helical spring 33 surrounding the pin shank 29 has its ends engaging the plug 27 and the head 30. A plurality of radial holes 35 in the portions 17 and 18 of the member 15 contain rods 36 whose inner ends project into the bore 20 against the head portion 31. Around each rod is a spring 38 abutting at one end 65 against the portion 17, and at the other end, against a shoulder 39 on an intermediate portion of the pin. Both ends of each rod are preferably rounded, and the outer ends are adapted to register in horizontal grooves 70 40 in the side wall 9 of the body. The depression of the pin head portion 31 under the influence of spring 33 normally forces the rods 36 into the grooves 40 to lock the plate 15 in place. By manually pressing the cam head 31 upwardly by means of an implement through the passage 22 the rods under the influence of springs 38 retract 75 from the grooves 40 and permit withdrawal of the closure plate 15. The rounded outer ends of the rods 36 assist the reinsertion of the plate 15 in the casing 8 without manipulating the head 31. A mass of sealing wax or other sealing material may be inserted in the cavity 23 to prevent unauthorized 80 access to the pin.

The top plate 11 has a lateral extension or runway 43 to accommodate which the wall 9 is cut away as at 44. In alignment with the extension the plate 11 has a rectangular opening 46 which slidably receives a vertically reciprocating cutter die with which its bounding edges cooperate to sever pieces from a flexible strip. The die is fast in 95 and depends from a flat head 48 preferably provided with a doubly inclined operating face 49. In the head are fixed downwardly directed rods 50 which slide in tubes 52 fast at their upper ends in openings 53 in the plate 11 at each side of the run. The lower 100 ends of the tubes are closed by portions 105 55

provided with holes 56 through which loosely pass reduced portions 58 of the rods 50 which form resultant shoulders 59. Disks or washers 61 are riveted to the enlarged lower 5 ends 62 of the rods exterior of the tubes, and serve as stops to the excessive upper 10 travel of the rods 50 under the influence of helical springs 64 surrounding the rod portions 58 and having their respective ends 15 engaging the shoulders 59 and tube closures 55.

The guiding means for the strip to be punched is a housing supported by the run 43 and the top plate comprising a top wall 15 66 having a marginal finger slot 67 and an intermediate rectangular opening 68 in the path of the die, side walls 69, an end wall 70, and attaching flanges 71 and 72 upon the side walls and end wall respectively, for the 20 reception of attaching screws 74. The end wall 70 at each side of its central portion is cut away to form passageways or openings 76. These openings permit the passage therethrough and the preservation of the 25 lateral margins of the advancing flexible strip from which the central portion has been cut away by the die 47. The portions of the strip cut by the die 47 are injected through the opening 46 into the casing 8 30 where they are preserved. The operation is effected by the downward blow of the operator's hand upon the head 48. Release of this downward pressure permits the springs 64 to instantly elevate the head to original 35 position. The strip to be operated upon is manually fed to the die by intermittently advancing the former along the run 43, with the lateral edges of the strip in contact with the guide walls 69 of the strip housing.

40 Integral with the rear of the casing wall 9 is a vertically disposed oblong block 83 provided in its rear face with a longitudinal dovetail groove 84, as shown in Figure 2. A suspension bracket 85, shown in detail in 45 Figure 6, is provided. In detail the bracket comprises a body 86, having in this instance integral with its upper end an acute angularly inclined arm 87 having upon its extremity a perforated attaching lug 88. A 50 similar lug 89 is located upon the bottom of the body. The perforations 90 and 91 respectively of these lugs are for the admission of screws to attach the bracket to the instrument board of an automobile. The 55 outer face of the body 86 has a longitudinally disposed rib 92 having undercut sides 93. This rib registers as a sliding fit in the groove 84, except that at its lower end the rib is broadened to form inclined lateral shoulders 95 which form a stop and support for the casing 8. By means of this 60 construction the casing 8 may be quickly and easily lifted out of or dropped into engagement with the bracket. The acutely angular 65 relation of the arm 87 results in tilting the

casing 9 downwardly when the bracket is mounted on the instrument board, thus increasing the visibility and manipulation of the flexible strip with relation to the operator seated in the automobile.

70

I claim:

1. In a device of the character set forth, a hollow body, a bottom in the body, a top provided with a cutter opening, parallel guides upon the top spaced from opposite sides of the opening, an abutment upon the top adjacent the opening disposed transversely of the guides and spaced at its ends from the guides, a head yieldingly supported by the body, and a die in the head cooperating with the opening.

75

2. In a device of the character set forth, a hollow body provided with grooves, a top provided with a cutter opening, an operating head yieldingly supported by the body exterior of the top, a die in the head registerable in the opening, a detachable bottom in the body, a post in the bottom provided with a bore extending into said bottom, a pin slidably mounted in the post, a tapering head on the post extending within the bottom, a spring in the post pressing against the head, radially disposed rods slidably mounted in the bottom with their inner ends in contact with the tapering head and having outer ends engageable in the grooves and springs on the rods engaging the bottom.

80

3. In a device of the character set forth, a hollow body provided in its lower portion with grooves, a top provided with a cutter opening, an external operating head yieldingly supported by the body and movable towards and from the head, a die in the head adapted to enter the opening, a detachable bottom in the body provided with a central passage and with a cavity into which the passage centrally opens, a post on the bottom provided with a central bore extending to said passage, a pin slidably mounted in the post in the bore, a cam head on the post in alignment with the passage, rods slidably mounted in the bottom abutting the cam head and laterally movable into the grooves, a spring in the bore depressing the cam head, and resilient means for pressing the rods 105 against the cam head.

95

4. In a device of the character set forth, a hollow body, a bottom detachably mounted in the lower portion of the body, a top provided with a cutter opening, an extension upon the top in alignment with the opening, depending tubes in the top, rods slidably mounted in the tubes, resilient means in the tubes for elevating the rods, an operating head on the rods above the top, a die on the head movable into the opening, a vertically disposed block on the body provided with a longitudinally disposed dovetail groove, and a bracket including a body, a longitudinally disposed rib on the body slidably seated in 115 120 125 130

the groove, and lateral shoulders on the bottom of the rib engageable with the lower end of the block.

5. In a device of the character set forth, a hollow body, a bottom, a top provided with a cutter opening, an operating head above the top, rods yieldingly carried by the top fast to the head and extending into the body, a die on the head adapted to register in the 10 opening, an upright block on the body provided with a vertical dovetail groove, and a

bracket comprising a body, a longitudinally disposed rib on the body slidably seated in the groove, an angularly inclined arm on the upper end of the bracket body, an attaching lug on the lower end of the bracket body, and an attaching lug on the end of the arm. 15

In testimony whereof I have affixed my signature.

FREDERICK H. JOHNSON.
